UNITED STATES PATENT OFFICE

WILLIAM R. LOGAN, JR., OF CARTHAGE, MISSOURI

DESIGN FOR A DECK OF PLAYING-CARDS

Application filed December 2, 1931. Serial No. 41,938. Term of patent 14 years.

To all whom it may concern:

Be it known that I, WILLIAM R. LOGAN, Jr., a citizen of the United States of America, and a resident of Carthage, Missouri, have invented a new, original, and ornamental Design for a Deck of Playing-Cards, of which the following is a specification, reference being had to the accompanying drawing, forming part thereof.

The drawing is a plan view of a deck of playing cards showing my new design.

I claim:

The ornamental design for a deck of playing-cards, as shown.

In testimony whereof I have signed this specification.

WILLIAM R. LOGAN, JR.
